UNITED STATES PATENT OFFICE.

WALTER E. CHRISTIAN, OF KENOSHA, WISCONSIN, ASSIGNOR TO THE BADGER BRASS MANUFACTURING COMPANY, OF KENOSHA, WISCONSIN, A CORPORATION OF WISCONSIN.

LAMP.

1,054,747.

Specification of Letters Patent.

Patented Mar. 4, 1913.

Application filed June 17, 1912. Serial No. 704,046.

To all whom it may concern:

Be it known that I, WALTER E. CHRISTIAN, a citizen of the United States, residing in the city of Kenosha, county of Kenosha, State of Wisconsin, have invented certain new and useful Improvements in Lamps, of which the following is a specification.

This invention relates to improvements in lamps, and refers more particularly to improvements in automobile lamps of that character in which the reflector is secured to and moves with the door structure, although in its broader aspects the invention is not necessarily so limited.

The salient object of the invention is to provide, in a construction of the above character, simple and improved means for detachably locking the reflector body to the door frame and at the same time rigidly confining the front glass or crystal in position.

Subsidiary objects are to provide a construction in which the reflector may be readily locked to the door structure or detached therefrom, and without the aid of screws, bolts or other extraneous fastening devices; to provide a construction in which the reflector is provided with a plurality of pivoted fingers or latch members adapted to have spring-locking engagement with slotted striker members carried by the door body; to provide a construction in which these locking devices are effectively concealed within the lamp and yet ready access may be had thereto by merely opening the door; and in general to provide an economical and yet effective structure of the character referred to.

40 The invention consists in the matters hereinafter described, and more particularly pointed out in the appended claims.

In the drawings—Figure 1 is a horizontal sectional view of an electric lamp equipped with my invention; Fig. 2 is a vertical sectional view taken on lines 2—2 of Fig. 1 and looking in the direction of the arrows; Fig. 3 is a fragmentary detail view showing one of the pivoted latch members; and Fig. 4 is a similar view showing one of the coöperating slotted striker members.

Referring to the drawing—1 designates the lamp body, to which is hinged, as shown at 2, the door frame 3, which in the present instance comprises a ring 4 provided at its

outer edge with an inturned flange 5. The door is locked in closed position by means of a screw 6 and nut 7, the former being rigidly fixed in the boss 8 secured to the outer edge of the ring 4. When the door is closed, the screw lies within a forked bracket 9 riveted to the outer side of the lamp body, as shown at 10. The door may be locked or opened by merely turning the nut 7. The lamp is supported by means of the usual bracket 11 and confining screw 12, the bracket fitting over a post (not shown) carried by the car body.

Within the lamp body is seated the concave reflector 13, the rear end of which is apertured to receive a socket member 14, within which is supported suitable electrical connections 15 for the bulb 16. These parts, however, form no part of the present invention, and need not be described in detail.

As is seen more clearly in Fig. 1, the outer edge of the curved reflector 13 is provided with an annular rim or flange 17. The front glass or crystal 18 is secured between this flange 17 and the member 5 of the door frame by the novel mechanism now to be described. To the flange or rim 17 are secured a plurality of circumferentially disposed supporting blocks 19, to each of which is pivoted, as shown at 20, a spring latch member 21. The outer side of each of these latch members 21 is provided with a locking lug 22, and at its free end each latch member is turned up to form an ear 23 by which the latch member can be more readily forced into or out of locking position. As shown more clearly in Fig. 3, the main body of the latch member is inclined away from the supporting blocks 19, the arrangement being such that the latch members normally spring rearwardly or away from the blocks 19. Each of the latch members 21 is adapted to have locking engagement with a corresponding striker member 24 which is secured to the inner side of the ring 4 of the door structure. Each of these striker members 24 is provided at its inner face with a recess or slot 25 for receiving the lugs 22 of the latch members.

In locking the reflector to the door structure, the glass or crystal is first inserted in place and the reflector turned until the lugs 22 of the latch member are opposite the corresponding slots 25 of the strikers. By pressing on the inclined ears 23 the latch

members will be forced downwardly and at the same time swing on their pivots sufficiently for the lugs 22 to enter the slots 25. When pressure is released the lugs automatically snap into effective locking engagement with the striker members. It is to be noted that the ears 23 are so arranged relative to the pivoted latch members that by pressing down on the ears the latch members are not only forced downwardly, but inwardly sufficient for the lugs 22 to engage the slots 25. The latch members may be released by simply forcing the ears downwardly and outwardly until the lugs pass out of the slots.

The invention is not limited to the details of the invention shown except as set forth in the appended claims.

I claim as my invention:

- 20 1. In a lamp, the combination with a body portion, of a door structure secured thereto, a reflector within the lamp body and adapted to move with the door structure, and means for detachably locking the reflector to the door structure, comprising pivoted latch members secured to the reflector and coöperating striker members carried by the door structure.
- 25 2. In a lamp, the combination with a body portion, of a door structure pivoted thereto, a reflector within said lamp body and moving with the door structure, and means for detachably securing the reflector to the door structure, comprising a plurality of resilient latch-members secured to the reflector, and coöperating striker members secured to the door structure and having coöperative spring-locking engagement with said latch members.
- 30 3. In a lamp, the combination with a body portion, of a door member movably connected thereto, a reflector member within said body portion and adapted to move with the door member, and means for detachably locking said members together, comprising a plurality of spring latches carried by one member, and a plurality of striker members carried by the other member and having spring-locking engagement with said
- 35 4. The combination with a main body portion, of a member pivotally connected to said body portion, a second member within said body portion, and means for detachably locking said members together, comprising pivoted spring latches carried by one of said members, and coöperating strikers car-

ried by the other of said members and adapted to have spring-locking engagement with said latches.

5. In a lamp, the combination with a main body portion open at its outer end, of a door frame hinged to said body portion and comprising a ring provided at its outer edge with an inturned flange, a reflector within said body portion and provided at its outer edge with an outturned flange, a glass seated between said flanges, and means for locking the reflector to the door frame, comprising a plurality of spring latch members pivotally connected to said outturned flange and provided with locking lugs, and a plurality of striker members secured to the inner side of said ring and slotted or recessed to receive the locking lugs of said latch members.

6. In a lamp, the combination with a main body portion open at its outer end, of a door frame hinged to said body portion and comprising a ring provided at its outer edge with an inturned flange, a reflector within said body portion and provided at its outer edge with an outturned flange, a glass seated between said flanges, and means for locking the reflector to the door frame, comprising a plurality of slotted striker members secured to the side of said ring, and a plurality of latch members pivoted to the inner edge of said flange and each comprising a spring body portion, an outturned lug adapted to have locking engagement with the slot of the corresponding striker member, and an inclined ear portion secured to the outer edge of the latch member.

7. In a lamp, the combination with a main body portion, of a door member pivoted thereto, a reflector member within said body portion, a striker carried by one of said members, a spring latch pivoted to the other of said members and adapted to have locking engagement with said striker.

8. In a lamp, the combination with a main body portion, of a door member pivoted thereto, a reflector member within said body portion, a striker carried by one of said members, a spring latch pivoted to the other of said members and adapted to have locking engagement with said striker, said latch having an inclined extension at its free end.

WALTER E. CHRISTIAN.
